UNITED STATES PATENT OFFICE.

GEOERGE W. FOGELSONG, OF IDAHO FALLS, IDAHO.

LEVELING INSTRUMENT.

1,220,407.

Specification of Letters Patent. Patented Mar. 27, 1917.

Application filed January 6, 1915. Serial No. 848.

To all whom it may concern:

Be it known that I, GEORGE W. FOGELSONG, a citizen of the United States, residing at Idaho Falls, in the county of Bonneville and State of Idaho, have invented certain new and useful Improvements in Leveling Instruments, of which the following is a specification.

My invention relates to leveling instruments.

The primary object of my invention is to provide a leveling instrument of a construction which will eliminate the use of the well known spirit level which at best gives the operator but a general idea as to the true angle or verticality of the particular plane involved.

Another object of my invention is to provide a leveling instrument wherein no easily breakable parts, such as ones of glass, are unprotected, and wherein the particular angle of a plane may be ascertained by observing indicating means at the side or top of the article.

A still further object of my invention is to provide a leveling instrument which is simple in construction, efficient in operation and durable in use and capable of being easily manufactured at low cost.

With these and other objects in view, my invention relates to such details in construction, combination and arrangement of parts, as will be illustrated in the accompanying drawings, described in the following specification and set forth in the claims.

In the drawings:—

Figure 1 illustrates an embodiment of my invention in side elevation;

Fig. 2 is a top edge or plan view of the embodiment of my invention showing to advantage the sight opening;

Fig. 3 is a cross sectional view taken on the line 3—3 of Fig. 2;

Fig. 4 is a longitudinal sectional view taken on the line 4—4 of Fig. 2, and

Fig. 5 is a perspective view of my preferred form of indicator.

In the drawings, like reference characters designate like or similar parts throughout the views.

The preferred embodiment of my invention consists of a stock 1 which has a central sight opening 2 provided therein. The opening 2 communicates with a recess 3 extending completely through the stock 1. Seated within the recess 3 is a hollow container or

casing 4 which is flatly cylindrical in configuration and which is constructed of transparent material such as glass. Casing 4 due to its cylindrical form has two side walls 5 and 6 and extending at a right angle to the walls 5 and 6 is a peripheral wall 4. The side walls are disposed within the recess 3 with their outer faces flush with the surfaces of the sides of the stock 1. Provided at the center of the side walls on their inner surfaces are bearing notches 8 and 9. Opening 2 is of less width than the stock 1 so that bridge portions 10 are provided on the upper face of the stock to retain the casing 4 within the recess 3 which guards the glass container against fracture.

In the casing I mount an indicator 11 which is formed of a single piece of flexible wire and is provided with indicator members 12 extending transversely of the stock and container and terminating short of each other. The indicator 11 has side arms 13 which are bent inwardly at 14 and outwardly and then inwardly to form bearing portions 15. Members 12 are terminations of arms 13. These portions 15 extend into the notches 8 and 9 whereby the indicator is pivotally mounted. Below the portions 15 the arms 13 have downwardly converging portions 17 which are connected by a transverse portion 18 on which is mounted a weight 16. On the peripheral wall 4 is provided an outwardly extending neck 19 normally closed by a stopper 20 removably fastened therein. A quantity of equilibrant or equilibrizing liquid is preferably contained within the casing 4. In order to enable the angle of the plane in question to be ascertained, suitable graduations or indications 21 are provided on the peripheral wall 4 of the casing and indications or graduations 22 are provided on either or both of the sides 5 of the casing, to coöperate with the indicator. The stock 1 is preferably cut away at 23 to provide a groove to permit the neck 19 to slide in while positioning the container within the recess 3. It will be noted that the projecting neck 19 by its engagement in groove 23, prevents turning of the container relatively to the stock and that it thereby mounts the graduations 21 in proper position for observation through opening 2. Plates 24 may extend across the sides 5 of the container and be fastened as by screws 25 to the stock, in order to secure the container within the stock.

In assembling the parts, the container while empty has the indicator inserted through the opening at neck 19. In view of the fact that this indicator is yieldable, the 5 arms 13 may be moved toward each other so as to render the indicator bendable to a slight width in order to pass through the opening at the neck. The arms 13, after the indicator is within the container, will yield away 10 from each other at the bearing portions 15 so that the bearing portions 15 will extend into the bearing notches 8 and 9. Thus the spring action of the indicator maintains the bearing portions 15 in engagement with the 15 notches. After the indicator has thus been inserted into the container, the equilibrant 21 is poured thereinto and the stopper 20 is then applied to the opening of neck 19. Thereupon the casing is moved transversely 20 of the stock 1 so that the container will move into recess 3 and the neck 19 will move into groove 23. After the container is thus mounted, the plates 24 are screwed to the stock. As far as fastening of the container 25 is concerned, but a single plate 24 need be provided, and this one be fastened on the side of the stock where the groove 23 opens. However in addition to serving as fastening means, the plates 24 serve as guards or 30 shields for the container to prevent fracture, and therefore two of the plates 24 are preferably provided.

In use, the stock 1 is placed against the desired surface. As the bearing portions 15 pivotally mount the indicator in the bearing recesses 8 and 9, this indicator will always seek the vertical. In order to promptly steady the indicator, the equilibrant 21 is provided. The weight 16 is provided to 40 maintain the indicator in a vertical position and when the indicator vibrates rapidly, the equilibrant acts on the arms 17 thereof and on the weight to quickly steady the indicator. In ascertaining the angularity of various 45 planes, the stock of course together with the container moves relatively to the indicator whereby, the different indications at 21 and 22 will be brought opposite the members 12 so that the correct indications may 50 be observed through the sight opening 2 or at either side of the stock.

As merely the preferred embodiment of the invention has been illustrated and described, it is to be understood that changes 55 in the details of construction may be resorted to without departing from the spirit and scope of the invention.

Having thus described my invention what I claim is:—

60 1. A level having a frangible casing, an indicator within said casing, means to cause said indicator to seek the vertical, a stock provided with a recess in which the casing is positioned and provided with a groove, 65 said casing having an extension for inser-

tion of the indicator and an equilibrant, said casing being positioned in said recess, and said extension being positioned in said groove to prevent turning of the casing relative to the stock.

2. A level having an indicator casing, an indicator within said casing, a stock member provided with a sight opening, a recess communicating with the sight opening, one of said members having a groove, the other of 70 said members being provided with an extension, said groove extending but partly across its respective member, said casing being mounted in said recess below the sight opening, and said extension being mounted in 75 said groove, said casing having indications on one side of the casing secured to the stock, and the said fastening member securing the casing in place with the extension in the groove and leaving substantially the said 80 85 graduations only, exposed.

3. A level having a casing, said casing being provided with an opening, an indicator yieldable for insertion through said opening, means to mount the indicator interiorly 90 of the casing, and means to cause said indicator to seek the vertical.

4. A level having a casing provided with bearing means interiorly thereof, said casing being provided with an opening, an indicator insertable through said opening, means to cause said indicator to seek the vertical, said indicator having a plurality of relatively movable arms, and means on one of 95 said arms to engage said bearing means. 100

5. A level having a casing, said casing being provided with an opening, an indicator insertable through said opening into the casing, means to cause said indicator to seek the vertical, said indicator being yieldable 105 for contraction while passing through the opening, and means to mount the indicator within the casing.

6. A level having a casing, an indicator within the casing having arms, said arms 110 being relatively yieldable and provided with indicator members at their free ends, said casing being provided with indications with which said members register during use, each of said arms being provided with a bearing 115 portion, means to mount the bearing portions on the casing, means to weight said arms, and means to connect the arms and mount the last mentioned means.

7. A level having a casing, said casing being provided with an opening, an indicator insertable through said opening having relatively movable arms, means to weight the arms at one end, bearing portions provided on the arms, said casing being provided with 120 means to pivotally mount said bearing portions, and an indicator member being provided on one of said arms.

8. A level having a casing, said casing being provided with an opening and with 125

graduations, an indicator within the casing having arms movable relatively for contraction to permit passage through said opening, said arms at their lower extremities 5 being joined by a transverse arm, a weight mounted on said transverse arm, said first mentioned arms intermediate their ends being provided with bearing portions, said casing being provided on the interior thereof 10 with bearing notches into which said bear-

ing portions spring for pivotal mounting, and one of said first mentioned arms being provided with an indicator member to register with said indications.

In testimony whereof I affix my signature 15 in presence of two witnesses.

GEORGE W. FOGELSONG.
